ALTAR CLOTH OR SIMILAR ARTICLE

Otto Frei, Palisades Park, N.J., assignor to Otto A. Scheurmann, Ridgewood, N.J.

Application January 7, 1959, Serial No. 54,061

Term of patent 7 years

(Cl. D92—1)

The figure is a plan view of an altar cloth or similar article embodying my own design.

The design unit shown in the drawing between the end line and the dot and dash line is repeated in regular succession along one end of the fabric.

I claim:

The ornamental design for an altar cloth or similar article, substantially as shown.
